CLAIM

The ornamental design for a bench with tubular legs, substantially as shown and described.

DESCRIPTION

FIG. 1 is a frontal perspective view showing a bench with tubular legs according to my new design;

FIG. 2 is a right side view thereof, the left side view being identical and opposite hand;

FIG. 3 is a top plan view thereof;

FIG. 4 is a front elevation view thereof;

FIG. 5 is a bottom plan view thereof; and,

FIG. 6 is a back elevation view thereof.
